UNITED STATES PATENT OFFICE.

LUCIUS J. KNOWLES, OF WORCESTER, MASSACHUSETTS.

IMPROVEMENT IN YARN-BEAMS FOR LOOMS.

Specification forming part of Letters Patent No. **159,686**, dated February 9, 1875; application filed January 28, 1875.

To all whom it may concern:

Be it known that I, LUCIUS J. KNOWLES, of the city and county of Worcester, and Commonwealth of Massachusetts, have invented certain new and useful Improvements in Yarn-Beams for Looms; and I do hereby declare that the following is a full, clear, and exact description of the same, reference being had to the accompanying drawings, forming a part of this specification, and in which—

Figure 1 represents a side view of one of my improved yarn-beams for looms. Figs. 2 and 3 represent longitudinal sections, as indicated by dotted lines A B and C D. Fig. 4 represents an end view of the beam. Fig. 5 represents a cross-section of the beam, cut through the center, and Fig. 6 represents an inside view of one of the cast-iron heads, as will be hereafter explained.

To enable those skilled in the art to which my invention belongs to make and use the same, I will proceed to describe it more in detail.

Combined wood and iron yarn-beams for looms, as constructed previous to my invention, were found very objectionable. The yarn-supporting part A of the beam was provided with iron heads B, having smooth inner sides to fit against the ends of the body part A, and were secured thereto by means of joint-bolts, the nuts being dropped into holes cut in the body part A, into which the bolts were screwed through holes in the iron heads and holes bored longitudinally into the ends of the body part A, and, as the nuts had to be dropped down some distance below the outer surface of the body of the beam, the bolts were brought very near the journal C of the beam, which required them to be turned very tight in order to hold the heads with any degree of firmness, and even then constant jarring of the loom, in connection with the friction-straps arranged to fit into the flat grooves a of the heads, caused the heads to work loose and spring, thereby allowing the threads to work down between the ends of the body A and its heads, so that when the joint-bolts were turned up to tighten the heads threads were liable to be caught between the heads B and the ends of the body A, thereby rendering it impossible to weave off the entire yarn from the beam, and involv-

ing quite a loss in consequence of this waste of yarn. Still another and more serious objection exists to the use of such old beams. If one of the joint-bolts happens to strip its nut-thread while it is being turned up to keep the head tight during either the process of filling the beam with yarn, or that of weaving it off, there is no way of repairing the breakage until the yarn is removed from the beam, and the attempt to weave it off would often be impossible, while, under the most favorable circumstances, the operation would be attended with great difficulty, owing to the unequal tension of the selvage-threads upon the end of the beam where the breakage of the beam-head fastening had occurred. Those accustomed to superintend the operation of weaving are well aware of the great and serious evils and losses which result to manufacturers from this cause.

To remedy the foregoing and other objections which might be named to the use of the old style of loom-beam is the object of my present invention. The iron heads B are made or cast with projections f, the outer edge of which, when the beam is finished, comes flush or even with the outer surface of the body part A of the beam, said projections f fitting into corresponding notches or recesses cut in the ends of the beam, as indicated in Fig. 3. Joint-bolts for fastening the heads to the body part are discarded entirely, and long rods b are employed, and which rods extend the entire length of the body part A, with their ends extending through the heads B sufficiently far to receive the holding-nuts e, which are screwed upon the projecting ends of said rods, as fully indicated in Figs. 2 and 4. The rods b lie in grooves cut in the outer surface of the body part A, their outer edges coming about flush with the outer surface thereof. It will be observed that the rods b pass through holes in the heads B between the projections f.

The body part A may be made and secured to the journal C in the usual manner.

From the foregoing description it will be seen that by screwing up the nuts e upon the rods b the heads B can be securely fastened to the body part A, and that, too, by pressure applied nearly on a line with the outer surface of the body part A, and that in case one

of the rods gives out or breaks, or its thread be stripped while in use either in filling or while the yarn is being woven off, the rod may be removed and repaired and, then inserted, or a new thread may be cut on its end without its being removed.

It will also be observed that the projections *f* and the rods *b* will form a support to and prevent threads working down between the head and the ends of the body part *A* in case the heads happen to become loosened. The projections *f* serve the further purpose of rendering the connections of the heads *B* with the body part *A* more rigid, secure, and firm.

Having described my improvements in yarn-beams for looms, what I claim therein as new and of my invention, and desire to secure by Letters Patent, is—

The combination, with the body part *A* and heads *B*, of the longitudinal head-holding and yarn-supporting rods *b*, head-holding and yarn-supporting projections *f*, and holding and tightening nuts *e*, substantially as and for the purposes set forth.

LUCIUS J. KNOWLES.
